DESIGN FOR A JACKET

Simon Etkin, New York, N. Y.

Application July 16, 1938, Serial No. 78,526

Term of patent 3½ years

To all whom it may concern:

Be it known that I, Simon Etkin, a citizen of the United States of America, residing in New York city, in the Borough of Manhattan, county and State of New York, have invented a new, original, and ornamental Design for a Jacket, of which the following is a specification, reference being had to the accompanying drawing, forming part thereof, wherein,

The design comprises a jacket having a cloth back, tie sash and full sleeves tucked at the wrist in the manner disclosed in combination with the fur front and the fur-faced collar and lapels, as shown.

I claim:

The ornamental design for a jacket, substantially as shown and described.

SIMON ETKIN.
